MACHINE FOR WORKING PAPER STOCK
AND SIMILAR MATERIALS

Anton Joseph Haug, Nashua, N. H.

Application June 4, 1938, Serial No. 211,906

9 Claims. (Cl. 92—26)

This invention relates to machines designed primarily for use in crushing and refining the coarser constituents of paper stock such, for example, as the materials rejected by the pulp screens. It should be understood, however, that the invention is equally useful in machines designed for other purposes, especially those required in preparing materials from which paper, paper board, wall board, and similar products are made. For convenience such materials will hereinafter be referred to as "paper stock."

The invention aims to improve machines of this type with a view to simplifying their construction, increasing their capacity without correspondingly increasing their dimensions, enlarging their range of usefulness, and generally improving and perfecting them.

The nature of the invention will be readily understood from the following description when read in connection with the accompanying drawings, and the novel features will be particularly pointed out in the appended claims.

In the drawings,

Figure 1 is a longitudinal, vertical section illustrating a preferred embodiment of the invention;

Fig. 2 is a transverse, vertical, sectional view approximately on the line 2—2, Fig. 1;

Fig. 3 is a plan view of a portion of the yoke shown in Figs. 1 and 2, illustrating the means for adjusting the relationship of one of the crushing rolls to the inner surface of the casing or drum of the machine;

Fig. 4 is a sectional view of a roll bearing and the parts immediately associated with it;

Fig. 5 is a face view of the sealing plate at the inlet end of the machine;

Fig. 6 is an edge view of said plate and parts immediately adjacent to it;

Figs. 7 and 8 are vertical and face views, respectively, of the sealing means through which one of the rolls extends at the discharge end of the machine;

Fig. 9 is a transverse, sectional view of the conduit extending centrally through the cylinder;

Fig. 10 is a perspective view of one of the bearing blocks shown in Fig. 1; and

Fig. 11 is a perspective view of a portion of the spider in which the bearing block is mounted.

Referring first to Fig. 1, the machine there shown comprises a casing or drum in which the stock is confined during the treatment of it, this casing including a cylinder 2 and, if desired,

a jacket 3 encircling it and providing a space through which steam, water, or the like, may be circulated in order to maintain the desired temperature conditions. At the left-hand end of the cylinder the casing is provided with an inlet section 4 having an intake chute 5, while at its opposite end it includes an outlet section 6 having a discharge opening or chute 7. A base 8 supports the casing. Mounted inside the cylinder are several rolls, one of which is shown at 10. These rolls may be provided with smooth or grooved surfaces, as desired. The particular machine shown in Figs. 1 and 2 is equipped with three rolls, although this number may be varied within reasonable limits and a greater number of rolls often is used.

An important feature of the invention resides in means for supporting these rolls in their co-operative relationship to the cylinder. As shown in Figs. 1 and 2, the machine includes a main shaft 12, the opposite ends of which are supported in bearings 13 and 14. A driving pulley 12a is mounted on one end of the shaft 12. Secured rigidly to the left-hand end of the shaft is a spider 15 provided with three radial slots to receive the bearings for supporting the left-hand ends of the three rolls. These bearings may be made of any suitable construction, but I prefer for most purposes to make them of non-metallic materials, such as Bakelite, Micarta, or some similar non-metallic material. In other cases it is preferable to make them of some of the usual bearing metals, and in still other cases of combinations, such as a cast or steel bearing block equipped with a non-metallic bearing bushing for the end of the roll to run in. The particular bearing shown in Figs. 1, 2 and 10 for supporting the lower roll 10 consists of a metal block 16 equipped with a bushing a made of one of the non-metallic materials just mentioned. This block is mounted to slide in between non-metallic guide pieces 17—17, best shown in Fig. 11, the block being provided with flanges b—b to bear against said guide pieces to take end thrust. A strong spring 18, interposed between the spider 15 and the bearing block 16, tends to force the latter outwardly radially, but a plunger 20, Fig. 4, bears on the outer side of said bearing and is backed up by a spring 21, much stronger than the spring 18, the former being seated in the bottom of a cavity formed in a gland 22. This gland is screw-threaded through a wall of the yoke 23 which encircles the spider and is secured to it. The stem of the plunger 20 projects through the bottom of the

gland and has a nut 24 screw-threaded on it. In Figs. 10 and 11 the sockets in which the ends of the spring 18 are seated are shown at c and d, respectively, it being understood that the bearing block 16 is shown in Fig. 10 upside down with reference to the parts in Fig. 11.

The same bearing construction is provided at the opposite end of the roll 10 to support it. It will be evident, therefore, that this roll normally floats between the springs 18 and 21. Thus when the machine is in operation the roll has both a rotative movement around its own axis and also an orbital movement around the main shaft 12. Consequently, the centrifugal force developed by the latter rotation tends to move the roll outwardly toward the inner surface of the cylinder 2, this force thus acting on the roll in the same direction as the springs 18 at its opposite ends. By adjusting the nuts 24, the tension or compressive force exerted by the springs 21 may be made to overcome the two forces urging the roll outwardly, and the preponderance of effort of the springs 21 may be made substantially as great as desired within the limits of design of these parts.

Also, by adjusting the glands 22 at opposite ends of the roll 10, the operating clearance between the surface of the roll and the inner surface of the cylinder 2 may be adjusted very accurately. This adjustment is made independently of the adjustment of the springs 21 and does not affect them materially. When the gland 22 has been adjusted to the desired degree, it may be secured in that position by a bolt 25, Fig. 3, projecting through any one of several holes 26 in the margin of the gland and threaded into the yoke 23. Preferably the yoke is made in three sections, as shown in Fig. 2. It fits snugly around peripheral portions of the spider and it is provided with lugs or ears f which overlap vertical faces on portions of the spider. Certain of the bolts 19 which hold the parts 17 in place extend through these ears and thus secure both the yoke and the members 17 to the spider.

Each of the other rolls is mounted in the same manner as is the roll 10 and can be adjusted in the same way, and such adjustment is important in producing the desired development of fiber in the material acted upon. It should also be observed that with this arrangement the rolls never touch the inner surface of the cylinder 2 during normal operation. In fact, the only time when there is actual contact between the rolls and the cylinder, with the usual adjustment, is when the machine is running at high speeds and a roll runs over a large hard piece of stock which displaces the roll to an abnormal degree, thus producing a rebound which, if there is no stock between the cylinder and the roll, may cause the roll to strike the inner surface of the cylinder. This arrangement, however, affords the desired yield of the rolls toward the axis of the drum during the operation of the machine, in addition to providing for the adjustment above described. It may also be noted that when the machine is running idly and with no stock in it, the rolls will not be revolved. They will start into rotation, however, just as soon as stock is fed into the cylinder. In other words, the rotation of the rolls around their own axes is caused by their action on stock interposed between them and the inner surface of the cylinder, combined with the fact that they are given a positive orbital rotative movement.

As shown in Fig. 4, the bearings 16, in addition to having bushings a of non-metallic material to

support the journal portions of the rolls, are also provided with bearing disks like that shown at e to take the end thrust of the roll, this thrust, in turn, being transmitted through the flanges b—b and the guides 17—17 to the spider 15.

The use of non-metallic bearing members of such a nature as those above described is an important advantage in a machine of this type, since these members can be lubricated by water. As shown in Figs. 1 and 4, the surfaces of the bearings toward the shaft 12 are provided with diagonal apertures 27 and with a central aperture under the spring 18, and jets of water are directed into these apertures from nozzles or orifices at the inner surface of a spray plate 28, Fig. 1. All of this bearing mechanism at the left-hand end, Fig. 1 of the machine is enclosed in a casing 30 so that the water used for lubricating purposes is confined, and it is discharged through the outlet 31 and conducted away through suitable connections, not shown.

Due to the fact that the stock when fed into the intake chute 5 naturally tends to accumulate there, it is necessary to provide some means for preventing the entrance of this material into the chamber in the casing 30 in which the bearings are mounted. For this purpose a sealing plate 32 is secured rigidly on the hub of the spider 15 and is held in place by several bolts, one of which is shown in Figs. 1 and 6 at 33, this bolt being threaded into a boss 34 projecting laterally from the adjacent face of the spider 15. The peripheral edge of this plate has grooves g cut in it, these grooves being spaced apart by substantially uniform distances, and the entire peripheral edge surface being so constructed. A jet of compressed air is directed continuously against this grooved edge of the plate through an aperture 35, Fig. 1, and the grooves are so inclined that the air is deflected inwardly by them toward the cylinder 2. Thus any stock which lodges on the edge of the plate is promptly ejected and forced backwardly into the intake chute.

The rolls extend through holes 36, Fig. 5, in this plate and these apertures are closed by plates 45 closely encircling the rolls and carried by them, one of these plates being shown at 37. It slides radially in guides 38—38 bolted to the plate 33.

At the opposite end of the machine a similar provision also is made for preventing the entrance of stock into the bearing chamber, this arrangement, however, differing from that at the intake end because the problem is not as serious at the outlet end of the cylinder. Here a sealing plate 40, Figs. 1, 7 and 8, is secured fast on the shaft 12 and is bolted to the spider 15 in the same manner as is the plate 32. Its peripheral edge, however, is grooved, as shown at 41, Fig. 7, to receive a sealing ring 42 having a running clearance with the disk, the ring itself being secured to the adjacent part of the frame. At this end, also, the end portion of the roll 10 projects through the disk and carries a plate 43 fitting closely therearound and sliding radially between guide plates 44—44. For convenience in assembly the plate 43 often is made in inner and outer sections, the inner section being split and the outer section being bolted to it to secure the two halves together. Both these plates and the plates 37 preferably are made of Bakelite, Micarta, or some other material adapted to be lubricated by water.

In using the machine the material to be refined is fed into the intake chute 5 by hand or by any suitable automatic mechanism, and some

means is necessary to feed this stock axially through the cylinder. In prior constructions this function has been performed by inclined vanes, for example, which utilize the rotative movement of the stock to feed it lengthwise of the drum. I have found, however, that this function can be performed more simply by directing jets of air or other fluid against the stock at suitably spaced intervals. Preferably such fluid consists of compressed air or steam. For this purpose the central portion of the main shaft 12 is encircled by a sleeve or conduit 46, coaxially disposed with reference to the shaft and preferably supported on hub portions of the spiders 15—15. Air or other gaseous fluid under pressure is led into this drum from any suitable source through a bore or hole 47 formed axially in the shaft 12 and extending from the right-hand end thereof, Fig. 1, to a point inside the conduit where it is connected with the space in the latter by means of a transverse hole 48. Through the wall of this conduit several orifices are drilled forming nozzles 50, Figs. 1 and 9, these orifices being so inclined that they direct jets of fluid outwardly and rearwardly toward the discharge end of the cylinder and spaced both circumferentially and longitudinally of the conduit 46. Consequently, as the shaft revolves these jets rotate with it and they act on the stock to move it toward the outlet and thus to cause any given portion of stock to be subjected to a great number of rolling or crushing operations as it is moved through the machine.

This arrangement not only simplifies the construction of the machine and reduces the expense of manufacture but, in addition, it increases the capacity of the machine for given dimensions by permitting a freer movement of the stock through it. In treating coarse and very fibrous stocks, this added freedom is important in substantially eliminating any tendency to plug the machine. It is obvious that in such an arrangement the rate of feeding movement of the stock through the machine can be controlled merely by manipulating the valve which controls the flow of air or steam to the nozzles. The use of air jets to feed the stock through the cylinder eliminates the necessity for using scrapers as in applicant's prior Patent No. 1,443,410 and thereby affords room for more rolls and, in addition, leaves the refining chamber relatively unobstructed for the free feeding of the stock therethrough. This is a very important advantage in applicant's refiner because it handles materials containing such a small proportion of water that they do not flow and therefore must be propelled.

When the stock reaches the discharge end of the cylinder it either drops through the outlet 7 or is discharged by the scrapers 51 secured to the sealing plate 40.

An important advantage of the construction above described is that the spiders, conduit 46, the rolls and their bearings, can all be assembled as a unit and then inserted endwise through the casing. Afterward the yokes can be put in place, the adjustments made, and finally the casings 30—30 set into place. The machine can be disassembled by reversing these steps. Because of the fact that the interior of the cylinder is open, more rolls can be used in a cylinder of given dimensions than would otherwise be possible, and the efficiency of the machine accordingly can be correspondingly increased. It will be understood that the opposite ends of each roll can move radially, independently of each other, 75

so that the rolls can adjust themselves automatically to differences in thickness of the stock at the intake and discharge ends of the machine.

While I have herein shown and described a typical embodiment of my invention, it will be understood that the invention may be embodied in other forms without departing from the spirit or scope thereof, as by inverting the operation, i. e., holding the spiders 15 and shaft 12 against rotary movement, and rotating the drum or casing 2 relative thereto; that it is applicable to operation on other materials than that specifically mentioned, that some features of the invention are useful in other types of refiners, and that the various features of the invention may be used independently of the others.

Having thus described my invention, what I desire to claim as new is:

1. In a machine for working paper stock, or the like, the combination of a casing provided with an approximately cylindrical inner surface; a roll in said casing extending longitudinally thereof, and means supporting said roll for rotation around its own axis and for movement toward and from said surface; said means comprising a bearing for one end of said roll, a spider in which the bearing is mounted for sliding movement toward and from the axis of said surface, opposed inner and outer springs acting on said bearing to support it resiliently in its operative position, means for adjusting the tension of said outer spring to a predetermined degree effective to overcome centrifugal force, and additional means for adjusting said bearing to predetermine the spacing of said roll from the inner surface of said casing while maintaining said spring tension adjustment undisturbed.
2. In a machine for working paper stock, or the like, the combination of a casing provided with an approximately cylindrical inner surface; a roll in said casing extending longitudinally thereof, and means supporting said roll for rotation around its own axis and for movement toward and from said surface; said means comprising a bearing for one end of said roll, a spider in which the bearing is mounted for sliding movement toward and from the axis of said surface, opposed inner and outer springs acting on said bearing to support it resiliently in its operative position, means for adjusting the tension of said outer spring to a predetermined degree effective to overcome centrifugal force, and a gland mounted for adjustment toward and from said axis and in which said spring and its adjusting means are supported for movement with said gland, whereby the adjustment of said gland serves to adjust the spacing of said roll relatively to said surface.
3. In a machine for working paper stock, or the like, the combination of a casing provided with an approximately cylindrical inner surface; a roll in said casing extending longitudinally thereof, and means supporting said roll for rotation around its own axis and for movement toward and from said surface; said means comprising a bearing for one end of said roll, a spider in which the bearing is mounted for sliding movement toward and from the axis of said surface, opposed inner and outer springs acting on said bearing to support it resiliently in its operative position, a plunger on which said outer spring bears, a gland supported for screw threaded adjustment toward and from said axis and in which said spring and plunger are mounted for movement with said gland, and a nut cooperating with said plunger

to adjust the pressure exerted by said spring, whereby said gland, spring and plunger cooperate to provide for the adjustment of said roll toward and from the inner surface of the casing and for the independent adjustment of the resistance offered by said spring to the movement of said roll toward said surface.

4. In a machine for working paper stock, or the like, the combination of a casing provided with an approximately cylindrical inner surface; a roll in said casing extending longitudinally thereof, and means supporting said roll for rotation around its own axis and for movement toward and from said surface; said means comprising a bearing for one end of said roll, a spider in which the bearing is mounted for sliding movement toward and from the axis of said surface, a shaft supporting said spider for rotation, a yoke encircling said spider and secured thereto, a spring between said bearing and said spider acting on the bearing to force it outwardly, an outer spring between said yoke and said bearing for forcing it inwardly, means for adjusting the tension of said outer spring to a predetermined degree effective to overcome the centrifugal force transmitted thereto by the roll, and a gland screw-threaded in said yoke for adjustment to predetermine the spacing of said roll from the inner surface of said casing, said spring and its adjusting means being supported on said gland.

5. In a machine for refining paper stock and the like, the combination of a casing adapted to retain the stock undergoing treatment, a shaft extending longitudinally through said casing, a series of rolls mounted in said casing extending approximately parallel to said shaft, spiders on opposite ends of said shaft, bearings supporting said rolls and mounted in said spiders for radial movement relatively to said shaft, springs interposed between said spider and said bearings for forcing the rolls outwardly, yokes encircling the respective spiders, additional springs interposed between said spiders and said bearings and serving to resist the outward movement of said rolls, means for adjusting the tension of the outer springs to a predetermined degree effective to overcome the centrifugal force of the rolls acting on them, and glands mounted in said yokes for radial adjustment and supporting the respective outer springs and the adjusting means for said outer springs, whereby the radial positions of said rolls and the tension of said springs may be independently adjusted.

6. In a machine for refining paper stock and the like, the combination of a casing adapted to retain the stock undergoing treatment, a shaft extending longitudinally through said casing, a series of rolls mounted in said casing extending approximately parallel to said shaft, bearings supporting said rolls and mounted in said spiders for radial movement relatively to said shaft, said casing having an approximately cylindrical stock treating chamber therein in which said rolls are mounted, a circular plate secured fast on said shaft to revolve therewith and closing one end of said chamber, the peripheral edge of said plate running closely adjacent to and being encircled by a surface of said casing, means for directing a jet of fluid under pressure against the

edge of said plate, said edge of the plate being grooved to deflect said fluid inwardly toward said chamber and thereby serving to dislodge stock adhering to the edge of said plate.

5 7. In a machine for refining paper stock and the like, the combination of a substantially horizontal casing provided with a cylindrical chamber to retain the stock undergoing treatment, a rotary shaft supported axially in said chamber, a roll in said casing extending approximately parallel to said shaft, means mounted on said shaft for supporting said roll for rotation around the axis of said shaft and also for rotation around its own axis in position to crush the stock 10 against the wall of said chamber, a sleeve encircling said shaft, and means for conducting fluid under pressure to the interior of said sleeve, said sleeve having a series of nozzles on the surface thereof for directing jets of said fluid diagonally outwardly and rearwardly where they will feed the stock being treated longitudinally through said chamber.

8. In a machine for refining paper stock and the like, the combination of a substantially horizontal casing provided with a cylindrical stock 25 refining chamber, a rotary shaft supported axially in said chamber, a plurality of rolls extending approximately parallel to said shaft, means supporting said rolls on said shaft for orbital rotation approximately in contact with the wall of said chamber where they serve to crush the stock against said wall, said means supporting said rolls for free rotation around their own axes due to their contact with the stock, and means 30 attached to said shaft for producing a series of jets of fluid spaced along the axial portion of the chamber and directed diagonally outwardly and rearwardly against said wall and the stock undergoing treatment so as to feed said stock longitudinally through said chamber, the parts being 35 so positioned that the chamber is substantially unobstructed except for said rolls and said jet producing means, and ample space thereby is provided in said chamber for the passage of the stock therethrough and for the stock feeding action of said jets.

9. In a machine for refining paper stock and the like, the combination of a substantially horizontal casing provided with a cylindrical stock refining chamber, a rotary shaft supported axially in said chamber, a plurality of rolls extending approximately parallel to said shaft, means supporting said rolls on said shaft for orbital rotation approximately in contact with the wall of 50 said chamber, where they serve to crush the stock against said wall, a series of nozzles mounted on said shaft for rotation therewith, and means for conducting fluid under pressure to said nozzles, the nozzles being positioned to direct jets of fluid 55 diagonally outwardly and rearwardly against the stock on the wall of said chamber where they serve to feed the stock longitudinally through the chamber, said parts being arranged to leave said chamber substantially unobstructed around said 60 rolls and adjacent to said wall so that the stock can be fed freely by said jets along the cylinder wall between the successive crushing actions exerted on the stock by the rolls.

ANTON JOSEPH HAUG.
